LUMINESCENT GAS LIGHTING APPARATUS

Joseph O. Cadieux, Meriden, Conn., assignor to
Connecticut Telephone & Electric Corporation,
Meriden, Conn., a corporation of Delaware

Application October 30, 1930, Serial No. 492,321

8 Claims. (Cl. 176—122)

One object of my invention is to provide a lamp capable of emitting light of two different colors. Another object is to provide a construction of this character which can be readily installed or replaced. Another object is to provide an installation capable of accommodating a multiple color lamp. Another object is to provide a construction in which the color from two lamps can be mixed.

10 In carrying out the invention the lamp consists of two helico-spiral tubes concentrically mounted in a single base. A socket contains protected contacts adapted to receive plug-in prongs of the lamp base. When the lamp is of 15 a type requiring high voltage, separate transformers are provided for the two tubes and these transformers are mounted in a housing which supports the socket. A single reflector is preferably provided surrounding the lamp 20 base and the tubes and an outer lens or glass may be provided.

Fig. 1 is a sectional view of a construction embodying my invention.

Fig. 2 is a front view of the lamp alone.

25 Fig. 3 is a circuit diagram showing the electrical parts of the apparatus.

The tubes 5 and 6 are formed of suitable material and preferably coiled into spirals which are tapered so that they have some of the 30 characteristics of the helix. These tubes contain suitable gas such as neon, and electrodes adapted to the conditions of use. Different gases may be used in the different tubes or the desired colors such as red and green may be produced in other suitable ways. The ends of the tubes are supported in a base 7 which may be formed of moulded insulation and provided with 35 prongs 8, 9, 10 and 11, electrically connected with the electrodes of the respective tubes.

40 The socket 12 may also be formed of suitably moulded insulation and provided with two pairs of contact clips such as 13 and 14 to receive the prongs of the tube base. These clips are preferably housed in the socket and protected 45 by a plate or disc 15, of insulating material, through which the prongs can be inserted but which disc prevents accidental engagement with the clips. This disc may be held in place by a central rivet 12'. The circuit terminals may 50 be secured to the clips such as 13 and 14 by suitable tubular rivets such as 14'.

It will be seen that the two sections or tubes are concentrically mounted with the terminal ends of the tubes and the prongs extending 55 parallel with the common axes of the sections.

The terminal ends of each tube are arranged diametrically opposite each other, the ends of one tube alternating with the ends of the other tube so as to keep the parts of opposite polarity separated as far as possible within the limits of the device. The central section 5 extends outwardly in front of the outer section 6 so that the light from the central sections is not laterally obscured by the presence of the outer section.

When it is necessary to employ transformers, I use separate transformers 16 and 17 for the two tubes, which transformers will be designed to provide the proper voltage for the respective tubes. The transformers may be mounted in a housing 18, having a face plate 19 secured to it, for instance, by rivets or screws 20. The socket 12 may be secured to this face plate by suitable rivets or screws 21.

The reflector 23 may be of suitable character and is mounted concentrically of the socket and lamp base. A glass or lens 24 of suitable character is also preferably provided for protection of the tubes and for such modification of the light as may be desired. A casing 25 surrounds the lamp socket and reflector and has a spring ring 26 of the usual character, or other suitable means for detachably securing the glass 24 in place. The transformer housing may also be further protected by a casing 27 secured to the part 25 by fastening devices 28. An insulating washer or gasket 29 may be inserted between the parts 25 and 27 of the casing. The apparatus may be conveniently supported from a conduit or standard 30 representing a part of the usual metallic conduit system.

A relay 31 may be employed to suitably control the turning on and off of the current for the respective tubes.

It will be seen that this arrangement makes it possible for instance to employ a single lamp for producing red and green light suitable for traffic signal systems. Such a lamp can be made and sold and handled as a unit and is readily inserted, removed and replaced. It will be seen that the transformer housing can be separated from the usual electrical conduit tubes and that the outer casing of the lamp and the reflector are adapted to be secured as a unit to the transformer housing.

By the use of such a duplex or multiple color lamp it is possible to obtain a combined color signal indicating "caution" so that a single lamp unit can be used to produce "stop" "go" and "caution" signals all within a single reflector.

It is well understood that such incandescent gas tube lamps operate with a high degree of efficiency and at low cost. My present invention has the added important advantage of concentrating the signals in a single unit. This is not only convenient and a cheap method of installation but it provides the added advantage of locating all the signals concentrically so that the observer's attention is concentrated on a single point.

10 Although the apparatus is especially designed for traffic signal control, it will be obvious that it may be used for display and ornamental lighting effects. The center tube 5 preferably emits red light and the outer tube 6 green. The outer tube is somewhat longer than the inner and may require a different transformer.

I claim:

1. A multiple tube lamp comprising two helico-spiral sections mounted one within the other, the inner section being arranged in front of the outer section, said sections have terminal ends extending substantially parallel to the axes of the sections and spaced apart approximately ninety degrees around the axis of the lamp.

20 2. A duplex lamp tube comprising two spiral sections arranged one within the other, the inner section being conical in shape and projecting beyond the general plane of the outer section and having two terminal ends projecting from the rear parallel with the axis of the section, the outer section having two terminal ends projecting from the rear and parallel with the axis of the section.

30 3. A multiple tube lamp comprising two helico-spiral sections arranged one within the other, and a common base having contact prongs arranged in alternate pairs projecting parallel with the axes of the sections, the inner section having two terminal ends mounted in the base and connected to two of the opposite prongs and the outer section having two terminal ends mounted in the base and connected to the alternate prongs.

45

4. A luminescent gas lamp comprising a plurality of gas-filled tubes concentrically and spirally disposed and a common supporting base for said tubes having contact terminals parallel to the axis of the tubes, the latter having the ends thereof adjacent to, and electrically connected with, said terminals and being adapted to emit different colored lights when energized.

5. In apparatus of the class described, a plurality of curved neon tubes, the convolutions thereof being in substantially conic alignment, an insulating base having the ends of said tubes imbedded therein, contact terminals protruding from said base and having electrical engagement with the ends of said tubes, and means for removably mounting said base, whereby said terminals are connected to a source of electrical energy.

6. In apparatus of the class described, a plurality of neon bulbs adapted to emit different colored lights, said bulbs being interwoven in the form of conical helices, means for mounting said bulbs in a portable base, and means in said base for transmitting electric energy to said bulbs.

7. In apparatus of the class described, a plurality of tubular neon lamps interwoven in the form of conical helices, a portable base having the ends of said lamps imbedded therein, and means in said base for independently connecting each of said lamps to a source of electrical energy.

8. In lighting apparatus, a plurality of tubes containing gas adapted to be rendered luminescent by an electric current, said tubes having the ends thereof imbedded in a free insulating base, and the body portions thereof wound into cooperating helico-spirals, said gas being adapted to emit different colors of light when said tube ends are connected across high-tension terminals.
